UNITED STATES PATENT OFFICE.

JOHN THOMAS PERRY, OF LA GRANGE, GEORGIA.

PORTABLE COUNTER.

SPECIFICATION forming part of Letters Patent No. 294,907, dated March 11, 1884.

Application filed December 11, 1883. (No model.)

To all whom it may concern:

Be it known that I, JOHN THOMAS PERRY, of La Grange, in the county of Troup and State of Georgia, have invented a new and Improved Portable Counter, of which the following is a full, clear, and exact description.

The object of my invention is to provide a new and improved portable counter for grocers, &c.

10 The invention consists in the peculiar construction and arrangement of the parts of a counter, as hereinafter more fully set forth, and pointed out in the claims.

Reference is to be had to the accompanying 15 drawings, forming part of this specification, in which similar letters of reference indicate corresponding parts in both the figures.

Figure 1 is a longitudinal elevation of my improved portable counter. Fig. 2 is a cross-sectional elevation of the same.

The counter consists of a longitudinal box or frame, A, on the under side of which an axle, A', is journaled about one-third of the length of the counter from each end, on the 25 ends of which axles wheels A² are mounted, thus permitting of moving the counter about. For instance, the counter can be moved from one part of the store to another, as necessity may require; or it may be moved outside on 30 the sidewalk in case business is very pressing; or it may be moved out in case of fire, &c. The wheels are arranged at about one-third of the length of the counter from the ends of the same, to prevent too great an accumulation of 35 weight at the middle. On the box or frame A six standards, B, are erected, between the upper ends of which a series of hoppers, C, are held. If desired, the counter can be constructed with only four standards; or more 40 than six can be provided. As shown, the counter is divided into two sections of unequal length; but it can be divided into more sections, or the sections may be of the same length. In the left-hand section of the box or 45 frame A two horizontal rows of drawers, D, are arranged, each row containing three drawers. These drawers are to contain pepper, spices, soda, peanuts, ginger, or like articles. Below each row of drawers compartments E 50 are provided, for receiving boxes containing soap, soda, potash, &c. On the right-hand end of the front of the counter three bins, F,

are formed, each of which is provided with a quadrant-cover, G, at the front upper corner of the counter-box A, which covers G have 55 their ends secured to V-shaped frames H, pivoted at their apexes or at the united ends of the shanks to the sides of the bins, thus permitting of swinging the said covers upward in case some of the material contained in the bins 60 is to be removed from the same. These bins are to contain the different kinds of sugar. If any of the sugar is to be weighed, the cover of the bin is swung inward and upward, and as soon as sufficient sugar has been removed the 65 cover is swung down, thus preventing flies, &c., from passing into the bins. The covers or doors G swing very easily. On the top plate of the counter box or frame A a desk, J, is arranged, which is provided with a drawer 70 for money and another drawer for books, &c., the said drawer being held above that part of the counter-box provided with the drawers D. Two parallel tracks, K, are arranged longitudinally on the top of the box A, and on the 75 said tracks the wheels L of a counter-scale, M, run, thus permitting of moving the said scale rapidly to any part of the counter. The hoppers C are each provided with a hinged cover, C', and at the bottom with an aperture, e, below 80 which a funnel-shaped spout, N, is arranged. A gate or cover, O, is held to slide on the upper surface of the bottom of each hopper between two grooved cleats, O'. A handle-rod, P, secured to the bottom of the gate or slide O, projects through the aperture e, and has its outer end bent, as at P', the said rod being guided in a suitable staple on the under side of the bottom of the hopper. The front of each hopper is provided with an aperture, Q, behind which 90 a pane, R, of glass is held in grooved cleats R'. The said hoppers are to contain flour, rice, barley, grits, dry sugars, green and roasted coffees, and other similar articles. In front of the hoppers a shelf, S, is provided on 95 the standards B, on which shelf sugar-boxes, candles, canned goods, or other articles can be placed. Shelves T are arranged between the rear standards, B, on which shelves canned goods, bottled goods, &c., are to be placed. 100 On the end of the counter a box, W, for holding meal is held, which box is provided at the outer end with a leg, W', provided with wheels W². On the said meal-box a cheese box and

cutter or other receptacle can be placed. If any of the material contained in a hopper, C, is to be weighed, the scale M is run under the corresponding spout, and the gate O is opened 5 by drawing it out by means of its handle-rod P. When the desired quantity of material has passed upon the pan of the scale, the gate O is pushed back and the opening in the bottom closed. The scale can also be run to any desired part of the counter if goods from the drawers D or one of the bins G are to be weighed.

Having thus described my invention, what I claim as new, and desire to secure by Letters 15 Patent, is—

1. A counter provided with tracks on which a scale provided with wheels can run, substantially as herein shown and described.
2. The combination, with a counter, of a series of hoppers held above the same, and of a traveling scale on the counter, below the hoppers, substantially as herein shown and described.
3. A counter constructed with a series of hoppers held above the same, substantially as herein shown and described.
4. A counter provided with standards B, between the upper ends of which a series of hoppers are held, substantially as herein shown and described.
5. A counter provided with a series of hoppers held above the same, each of which hoppers is provided with a bottom opening and a sliding gate for closing the said opening, substantially as herein shown and described.
6. A counter provided with a series of hoppers held above the same, the spouts N, projecting downward from the bottom of the hoppers, the sliding gates O, and the bent rods P, secured to the gates, substantially as herein shown and described.

7. The combination, with a counter, of the hoppers C, each having an opening, c, in its bottom, the funnel-shaped spout N on the under side of each hopper, the sliding gate O, 45 the grooved cleats O', and the bent rod P, secured to the bottom of the gate, substantially as herein shown and described.

8. A counter provided with a series of hoppers having openings in their fronts, substantially as herein shown and described.

9. A counter provided with a series of hoppers having openings in their fronts and discharge-openings in their bottoms, the said discharge-openings to be provided with sliding 55 gates, substantially as herein shown and described.

10. The combination, with a counter, of the standards B, the hoppers C, held between the upper ends of the same, and of a shelf, S, in 60 front of the hoppers, substantially as herein shown and described.

11. The combination, with a counter, of the standards B, the shelves T, held between the standards, and of hoppers C, held between the 65 upper ends of the standards, substantially as herein shown and described.

12. The combination, with the counter A, mounted on wheels, of the box W, connected with the counter, and also mounted on wheels, 70 substantially as herein shown and described.

13. A counter provided with bins F, having quadrant covers, and with drawers D and a desk, J, substantially as herein shown and described.
